(57) **CLAIM**

The ornamental design for a tablet crusher, as shown and described in the drawings.

DESCRIPTION

FIG. 1 is a side perspective view of a tablet crusher of the present invention;

FIG. 2 is a side elevational view of the tablet crusher of the present invention, and which is duplicative of the reverse side thereof;

FIG. 3 is a storage end elevational view of the tablet crusher of the present invention;

FIG. 4 is handle end elevational view of the tablet crusher of the present invention;

FIG. 5 is a top plan view of the tablet crusher of the present invention; and,

FIG. 6 is a bottom plan view of the tablet crusher of the present invention;

FIG. 7 is a side perspective view of a tablet crusher of the present invention, with a removable container of plastic pouches used with the tablet crusher of the present invention; and,

FIG. 8 is a side elevational view of the tablet crusher of the present invention, and which is duplicative of the reverse side thereof, with a removable container of plastic pouches used with the tablet crusher of the present invention.

Shown in phantom lines in FIGS. 7 and 8 is a removable container of plastic pouches used with the tablet crusher of the present invention. These lines form no part of the claimed design, but are used to illustrate the operating environment of the present invention.
